HANDLE

Filed June 6, 1924

FIG. 1.

FIG. 2.

FIG. 3.

Inventor

Morris White

By

H. S. Moore

Attorney

UNITED STATES PATENT OFFICE.

MORRIS WHITE, OF NEW YORK, N. Y.

HANDLE.

Application filed June 6, 1924. Serial No. 718,248.

To all whom it may concern:

Be it known that I, MORRIS WHITE, a citizen of the United States, residing at New York city, in the county of New York and State of New York, have invented certain new and useful Improvements in Handles, of which the following, in connection with the accompanying drawings, is a specification.

10 This invention relates to improvements in handles or straps for bags, particularly those adapted for ladies' use, such as handbags, pocketbooks, and under-the-arm bags, although it will be apparent that the invention may be applied to many other types of devices.

The object of the invention is the provision of a strap or handle which may be extended upwardly from the bag to accommodate the hand, and which may be easily brought down flat against the bag with practically no effort, or which may even return itself automatically to the flat position when the hand of the person carrying the bag is removed from beneath the strap or handle.

An exemplary embodiment of my invention is illustrated in the drawings, wherein: Fig. 1 is a front elevation of a handbag having my improved handle attached there-

30 to;

Fig. 2 is a longitudinal section through one of the straps of the handle; and

Fig. 3 is a perspective, partly exploded view of one of the strap members.

35 Referring to these figures of the drawings, 1 designates a bag to which my improved handle is attached, and such bag may have the usual body portion 1^a, flap cover 1^b, and snap fastener 1^c, and when my improved handle is used with such a device it is preferably attached to the top surface of the upper part of the flap, as shown in Fig. 1. The two straps of the handle are attached at their outer ends 2 to the bag in any suitable manner, and preferably by the usual stitching (not shown). Each strap is made up of a somewhat stiff fabric 3, and I prefer to make this of a compound layer of paper board and scrim cemented thereto, but it will be quite obvious that any other suitable stiffening and strengthening member may be used. This stiffening and strengthening member is covered by a layer of material 4 having a finished and pleasing appearance, and the end of the strap, which is

stitched or otherwise attached to the bag, may be shaped in a pleasing manner, as for example, by tapering it out to a point. The covering material 4 is cut as at 5 and 6 for a reason to be referred to later, the cut extending from each edge of the covering material 4 to the edges of the stiffening member 3. A U-shaped buckle-like retaining member 7 or link is attached to the inner end of each strap by folding the inner end thereof over a rod 8 which connects the ends of the U-shaped member and this rod 8 is preferably swiveled therein. The members 7 and 8 are made of metal of a pleasing appearance, and the ends of the member 7 may be enlarged as at 9, these being perforated to accommodate the headed rod 8 made of the same metal. After insertion of the rod 8 through the perforations the unheaded ends may be hammered down with a suitable instrument to prevent the rod 8 from falling out of these perforations, the U-shaped member 7 and the rod 8 being preferably so assembled that the U-shaped member may turn freely on this rod without becoming detached therefrom.

The inner end 10 of the strap is bent around the rod 8 after the cut ends 11 of the covering material have been turned up, as shown in Fig. 3; and this end 10 which has been bent around the rod 8 is then laid flat upon the main portion of the strap, whereupon the flaps 11 are laid flat thereupon and adhesively attached thereto in order to give a pleasing appearance.

90 The handle comprises two like parts, each part comprising a strap member attached at one end to the article and having a buckle-like retaining member or link at its other end, and the strap member of each handle part passes through the retaining member of the other strap, as shown at 12 on Fig. 1.

100 The points of attachment of the handle to the bag are spaced from each other a distance less than the total length of the two straps in order that the handle may be raised away from the bag, as shown in Fig. 1, where the handle is in a more or less intermediately raised position.

105 Each of the U-shaped members 7 has such width and depth that the strap of the other half of the handle can move freely therein, without, however, making any of these parts unsightly; and I prefer the inner

surface of the member 7 to be of smooth metal as an aid to the free movement of the strap therein.

The stiffness of the strap members and their freedom in passing through the U-shaped member of the other half of the handle may be such that the handle will remain in any position until given a slight touch, whereupon it will fall flat against the bag; or this relation may be such that on removal of the hand from beneath the handle, such handle will automatically fall flat against the bag.

It is apparent that the two strap members of the handle will remain in substantial parallelism to each other, at least those parts thereof that are between the members 7, 7, except at the extreme raised position of the handle where the two strap members are permitted to and do assume an angular relation toward each other.

Having described my invention what I claim as new and desire to secure by Letters Patent of the United States is:

1. In combination an article and a handle therefor, said handle comprising two similar parts, each part comprising a strap member and a link at one end thereof, each strap member passing through the link of the other, the straps and the links being so proportioned that each strap passes freely therethrough, each strap being elastically flexible and having stiffness and tending to assume a predetermined contour, whereby the handle has a tendency to assume a position closely adjacent the article, the other end of each strap member being attached to the article, the points of attachment being spaced from each other a distance less than the sum of the lengths of both straps, the lengths and stiffness of the straps, their freedom of passage through the links, and the distance between the points of attachment of the straps to the article, being in

such relation to each other that when the handle is raised from the article for use the two parts of said handle will have a tendency to remain in such angular relation toward each other that they will not jam against each other until substantially the outermost raised position is reached, at which point the two straps assume such an angle each toward the other at their link ends that they jam.

2. In combination, an article and a handle therefor, said handle comprising two similar parts, each part comprising a strap member having a loop therein, a rod in said loop, a U-shaped buckle-like member swivelled on said rod, one end of each strap member being attached to the article, the points of attachment being spaced from each other a distance less than the sum of the lengths of both straps, each strap passing freely between the U-shaped member and the strap of the other part, each strap being flexible yet having rigidity with relation to the freedom of passage through the buckle-like member.

3. In combination, an article and a handle therefor, said handle comprising two similar parts, each part comprising a strap member folded over at its end to form a permanent loop, a round smooth metal rod in said loop, a smooth U-shaped metal buckle-like member swivelled on said rod, one end of each strap member being attached to the article, the points of attachment being spaced from each other a distance less than the sum of the lengths of both straps, each strap passing freely between the U-shaped member and the strap of the other part, each strap being flexible yet having rigidity with relation to the freedom of passage through the buckle-like member.

MORRIS WHITE.
